UNITED STATES PATENT OFFICE

OSBERT L. EDWARDS, OF HOPEWELL, VIRGINIA, ASSIGNOR OF ONE-HALF TO JAMES B. HAYWOOD, OF HOPEWELL, VIRGINIA

COMBINATION FOOT PIECE FOR FOLDING RECESS-TYPE BEDS

Application filed October 4, 1929. Serial No. 397,407.

The present invention relates generally to folding furniture and more particularly to folding recess type beds and has for its prime object to provide an improved foot 5 piece having a piece of furniture such as a folding dressing table or dresser incorporated therein so as to be disposed in a convenient and accessible position when the bed is folded down and to be out of the way 10 in a compact relationship with the bed when the bed is folded up. A still further very important object of the invention resides in the provision of an improved apparatus of this nature which is 15 simple in its construction, inexpensive to manufacture, compact and convenient in its arrangement of parts, strong and durable, not likely to easily become out of order, easy to manipulate, and otherwise thoroughly efficient and reliable in use and operation.

With the above and numerous other objects in view as will appear as the description proceeds, the invention resides in certain novel features of construction, and in 20 the combination and arrangement of parts as will be hereinafter more fully described and claimed.

In the drawing:

Figure 1 is a side elevation of a bed with 30 my improved features incorporated therein,

Figure 2 is a front end view thereof,

Figure 3 is a top plan view of the auxiliary pieces of furniture such as a dressing table or dresser with the mirror structure 35 folded up,

Figure 4 is an enlarged detail sectional view taken substantially on the line 4—4 of Figure 1,

Figure 5 is a sectional view taken substantially on the line 5—5 of Figure 4,

Figure 6 is a sectional view taken substantially on the line 6—6 of Figure 3.

Referring to the drawing in detail it will be seen that the numeral 5 denotes a frame 45 of any one of a large number of well known folding recess type beds. This frame 5 is swingably mounted in the back supporting structure 6 of conventional construction.

The numeral 7 denotes an inverted U-shaped foot piece which I have illustrated

by way of example. Hollow arms 8 project inwardly from intermediate portions of the sides of the foot piece 7 and are suitably braced through the medium of a vertical tubular brace member 9 and diagonal horizontal brace members 10.

Hingedly mounted sections or extensions 11 are mounted on the lower extremities of the sides of the foot piece. Block 12 is mounted in each side of the foot piece 7 and extends into the respective hollow arm 8 and receives the outer end of a bar 14 which extends between the legs of the foot piece 7 and is reduced intermediate its ends as at 16 and has a roller 15 journaled on the reduced portion thereof, anti-friction means being associated between the roller and the reduced portion 16 as is indicated at 17.

A spring 18 is disposed on the bar 14 and impinges against the block 12 and against a friction block 19 slidable on the bar. The numeral 20 denotes an auxiliary piece of furniture such as a dressing table or dresser including side rear legs 21 of hollow construction having vertical slots 22 in their upper ends through which the rod 14 extends and in the upper portions of these hollow legs 21 are inverted U-shaped guides 23 against which the friction blocks 19 are held by the springs 18 and in which extends the rollers 15 and it will be noted that the reduced portions 16 projects through a slot 25 opposite to slots 22.

Thus it will be seen that this piece of furniture 20 is capable of rocking and sliding 35 on the bar 14, so that the piece of furniture may be maintained substantially vertical during swinging movement of the bed to the dotted line position shown in Figure 1. When the bed is in its final vertical position, the piece of furniture is then permitted to move vertically and downwardly to assume that position shown in dotted lines in Figure 1 and to be retained in such position through the medium of the springs 18 edging the blocks 19 into frictional engagement with the inverted U-shaped guide members 23. Obviously, the springs 18 bearing against the block 19 will tend to center the piece of furniture so as to prevent binding of 90 95 100

the rear legs 21 of the piece of furniture against the ends of the tubular arms 8. It is also to be noted that each of the vertical brace members 9 at their upper ends are suitably notched or recessed conformably with the edge of the top 29 of the piece of furniture for receiving the adjacent rear corners of the top when the bed is in extended position and the article of furniture vertically disposed or in that position shown in Figure 1, this particular feature being more clearly illustrated in Figure 4.

A mirror 26 is hingedly mounted as at 27 on the crown or upper portion of the said inverted U-shaped foot piece 7 and held upright by braces 28 detachably engaged with the top 29 of the piece of furniture by extending into openings 30 and locked therein by means of removable pins 31. Wings 32 are hingedly connected to the sides of the mirror so that they may be swung in front of the mirror as indicated to advantage in Figure 3 and held in this position by suitable locking means such as a bolt and keeper structure 34.

When the bed is in a down position as shown in full lines in Figure 1 it will be noted that the bar 14 is located in the bottom ends of the slots 22 and 25. When it is desired to fold up the bed the braces 28 are released and the mirror swung rearwardly after the wings 32 have been folded in front thereof.

The frame 5 is then moved upwardly causing the bar 14 to move to the top ends of the slots 22 and 25 and then the piece of furniture will be lifted upwardly as the frame 5 continues to swing upwardly and will rock so as to be maintained in substantially vertical position finally taking the position as is shown to advantage in Figure 1 in dotted lines and, of course, then the bed is rolled back in its recess.

It is thought that the construction, operation, utility and advantages of this invention will now be apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In combination with a folding recess type of bed, wherein the latter comprises

a head piece, a foot piece, a frame rigidly connected at one end to the foot piece and pivotally connected at its other end to the head piece, a bar extending transversely of said foot piece, an article of furniture including a pair of rear legs and said rear legs respectively provided with a pair of longitudinally extending transverse slots receiving said transverse bar.

2. In a folding recess type of bed including a head piece, a foot piece, and a connecting frame pivoted at one end to said head piece and rigidly secured at its other end to said foot piece, inwardly directed hollow arms mounted on the foot piece, a bar extending transversely of the foot piece and having its opposite ends received in said arms, an auxiliary piece of furniture having legs of hollow construction with vertical slots through which the bar extends, guide members in the legs, friction blocks slideable on said bar, spring means for normally urging said friction block into engagement with said guide members, and rollers journaled on the bar and movable in said guide members.

3. In combination with a folding recess type of bed, wherein the latter comprises a head piece, a foot piece, a frame rigidly connected at one end to the foot piece and pivotally connected at its other end to the head piece, a bar extending transversely of said foot piece, an article of furniture including a pair of rear legs and said rear legs respectively provided with a pair of longitudinally extending transverse slots receiving said transverse bar, guide members in the legs, rollers journaled on the bar and movable in said guide members.

In testimony whereof I affix my signature.

OSBERT L. EDWARDS.
